UNITED STATES PATENT OFFICE.

KAZIMIER BOROVSKI, OF DETROIT, MICHIGAN.

WASHBOILER.

1,065,902.

Specification of Letters Patent. Patented June 24, 1913.

Application filed November 11, 1912. Serial No. 730,657.

To all whom it may concern:

Be it known that I, KAZIMIER BOROVSKI, a subject of the Emperor of Austria-Hungary, residing at Detroit, in the county of Wayne and State of Michigan, have invented certain new and useful Improvements in Washboilers, of which the following is a specification, reference being had therein to the accompanying drawing.

10 This invention relates to wash boilers, and the primary object of my invention is to furnish a wash boiler with a novel clothes holder that permits of clothes being elevated whereby water can readily drain from 15 the same and the clothes cooled to that extent that they can be easily removed from the wash boiler.

Another object of this invention is to furnish a wash boiler with a clothes holder 20 in the form of a foraminous body that can be easily, quickly and safely elevated relatively to the boiler to permit of water draining from the clothes.

A further object of this invention is to 25 furnish the bottom of a boiler with a novel heat distributor that facilitates the heating and boiling of water within the boiler.

A still further object of this invention is to furnish a boiler with a simple, durable 30 and inexpensive attachment that prevents clothes from being burned by the bottom of a clothes boiler.

With the above and other objects in view the invention resides in the novel construction, combination and arrangement of parts 35 to be hereinafter specifically described and then claimed.

Reference will now be had to the drawings, wherein:

40 Figure 1 is a side elevation of a clothes boiler in accordance with this invention, Fig. 2 is a longitudinal sectional view of the same, Fig. 3 is a vertical sectional view of the boiler, Fig. 4 is a side elevation of the clothes boiler showing the attachment thereof in an elevated position, and Fig. 5 is a horizontal sectional view of the boiler.

Further describing my invention in detail with reference to the accompanying 50 drawings, wherein like numerals denote corresponding parts throughout: 1 denotes an oblong receptacle having the shape of an ordinary clothes boiler and the upper edges of the receptacle, at the ends thereof are 55 provided with handles 2 whereby the clothes boiler can be easily moved. The bottom of

the receptacle has a plurality of openings 4 closed by conical-shaped nipples 5 extending into the receptacle. The inner ends of the nipples are provided with openings 6 in communication with a longitudinal closed heat conduit 7 that is in the form of a tube and spaced above the bottom 3 of the receptacle.

8 denotes guides carried by the outer sides of the receptacle 1, intermediate the ends thereof, said guides extending from the bottom to the upper edges of said receptacles. Slidably mounted in the guides 8 are supports 9 that have the upper ends thereof provided with cross heads or holders 10 arranged longitudinally relatively to the receptacle. The supports 9, adjacent to the heads 10 are provided with outwardly extending pivot pins 11 upon which are pivotally mounted the upper ends of rods 12. The lower ends of the rods are pivotally mounted upon pins 13 carried by the ends of a yoke 14 that surrounds one end of the receptacle 1.

The yoke 14 is fulcrumed upon stud bolts or pins 15 carried by the outer sides of the receptacle 1, adjacent to one end thereof. The yoke 14 intermediate the ends thereof has an offset portion 16 provided with a 85 handle 17 and this handle is adapted to be engaged by an angle keeper 18 pivotally mounted between apertured lugs 19 carried by the end of the receptacle. The angle keeper 18 retains the outer end of the yoke 90 in a lowered position and the inner end of the yoke in an elevated position whereby the supports 9 will be elevated and the cross heads 10 raised to a point above the upper edges of the receptacle. By swinging 95 the keeper 18 upwardly out of engagement with the handle 17, the supports 9 can be easily lowered.

Arranged within the receptacle 1 is a clothes holder 20 having the form of a 100 clothes boiler, this holder being telescoped by the receptacle 1. The upper edges of the holder 20 at the ends thereof have handles 21, similar to the handles 2, and at the sides of said holder there are outwardly 105 extending curved brackets or handles 22 adapted to be engaged by the cross heads 10 of the supports 9.

The bottom of the holder 20 is perforated, as at 23 and provided with an oblong opening 24. Arranged over the opening 24 and secured to the bottom of the holder is a semi-

2
cylindrical perforated casing 25 that provides clearance for the heat conduit 7. The sides of the clothes holder 20 are provided with large openings 26 screened by vertical parallel equally spaced bars 27.

5 With the clothes holder in a lowered position within the receptacle 1 clothes can be placed therein and safely boiled by the water within the receptacle 1, without any 10 danger of the clothes being burned or scorched against the heated bottom 3 of the receptacle. Heat is uniformly distributed and conducted in the bottom of the receptacle 1, whereby the contents thereof can be expeditiously brought to a boil.

15 After the clothes have been boiled the handle 17 of the yoke 14 can be lowered and locked in a lowered position by the angle keeper 18. As the yoke 14 is shifted the 20 supports 9 are raised and the clothes holder elevated to the position shown in Fig. 4. Water can then drain from the holder back into the receptacle 1 and then the holder removed from the cross heads 10 and the 25 clothes carried to a point for further washing operations.

The wash boiler in its entirety can be made of light and durable metal and of such sizes that it can be conveniently handled.

30 While in the drawing there is illustrated a preferred embodiment of the invention it is to be understood that the structural elements are susceptible to such variations and modifications as fall within the scope 35 of the appended claims.

What I claim is:—

1. A wash boiler comprising a receptacle having its bottom formed with a series of longitudinally alining openings, cone-

shaped nipples secured to the upper face of 40 said bottom and arranged over said openings, a cylindrical longitudinally extending heat conduit having said nipples connected thereto and communicating therewith, a clothes holder mounted in said receptacle 45 and having its bottom formed with an oblong opening, a semi-cylindrical perforated casing secured to the bottom of the holder and into which extends said conduit, said holder further having its bottom provided with perforations. 50

2. In a wash boiler, a clothes holder comprising a body portion having each of its sides provided with large openings, vertically disposed spaced parallel bars arranged within said body portion and at each of said openings, said body portion having its bottom formed with a longitudinally extending oblong opening, and a semi-cylindrical perforated casing secured to the upper face of said bottom and over said oblong opening, said bottom being further 55 perforated. 60

3. A wash boiler comprising a receptacle for a clothes holder, said receptacle having 65 its bottom provided with a plurality of longitudinally alining openings, cone-shaped nipples secured to the upper face of said bottom and arranged over said openings, and a longitudinally cylindrical closed heat conduit secured to the top of and communicating with said nipples. 70

In testimony whereof I affix my signature in the presence of two witnesses.

KAZIMIER BOROVSKI.
